UNITED STATES PATENT OFFICE

JOHN H. HOLLOWAY, OF LA FAYETTE, INDIANA

CARBURETOR

Application filed June 21, 1926. Serial No. 117,514.

My invention relates to specific ways and means for securing the following functions which are necessary to a high standard of performance in the art of carburetion and agreed to by those skilled in a knowledge of this art.

These may be briefly classified as follows:

1. Means for readily securing any air fuel ratio desired.
- 10 2. Least possible change in the predetermined air fuel ratio with variation in temperature.
3. Greatest amount of atomization of fuel with least loss in pressure through carburetor.
- 15 4. Thorough mixing of air and fuel before entrance into the intake manifold.
5. Avoidance of obstructions in the combustible mixture stream so that coalescence 20 of the fuel may be prevented or that original atomization may be maintained to the highest possible degree.
6. Easily operated throttle.
7. Device for providing temporary enrichment 25 of combustible mixture upon sudden opening of throttle such as required for maximum acceleration.
8. Freedom from moving parts and simplicity of construction.

30 The drawings illustrate various structures which embody my invention and meet the above requirements by the use of new and novel mechanisms.

In the drawings—

- 35 Fig. 1 is a vertical cross-sectional view of one embodiment of my invention as applied to a vertical outlet carburetor. Fig. 2 is a sectional view taken along the line 2—2 of Fig. 1. Fig. 3 is a partial section of the carburetor body showing the fuel feed duct, orifice plate, fuel nozzles, air ducts, and air bleed connections to fuel nozzles. Fig. 4 is a cross-sectional view of an air bleed duct showing means for altering the size of an air bleed orifice. Fig. 5 is a development of the carburetor body periphery showing location of air intake ducts and air bleed openings. Fig. 6 is an imaginary horizontal cross-sectional view of the carburetor body showing 45 the location of the air ducts, fuel nozzles, and

air bleed holes. Fig. 7 is a perspective view of the plate containing openings for connecting air bleed and fuel nozzle passages. Fig. 8 is a perspective view of the fuel orifice plate. Fig. 9 is a perspective view of a cylindrical throttle suitable for the use with a cylindrically bodied carburetor as shown in Fig. 2. Fig. 10 is a bottom view of the carburetor showing the plate covering the float chamber and carburetor body. Fig. 11 is a side view of another embodiment of my invention as applied to a horizontal outlet carburetor. Fig. 12 is a partial sectional view taken on line 12—12 of Fig. 11 through the body of the carburetor and throttle. Fig. 13 is a 60 sectional view taken on line 13—13 of Fig. 12 showing the air and fuel passages. Fig. 14 is a partial side and cut away view showing another embodiment of my invention as applied to a carburetor with a rectangular body and integral air cleaner. Fig. 15 is a 65 vertical sectional view through the carburetor body and throttle showing the air bleeds, air intake ducts, acceleration wells, fuel orifice plate, fuel ducts and throttle parts both 70 manual and automatic. Fig. 16 is a vertical sectional view through the carburetor body at right angles to the view in Fig. 15 showing the throttle, air cleaner, throttle lever and fuel duct to the float chamber. Fig. 17 is a 75 partial top view showing a flange for attachment to the engine manifold, and serrated flanges on the carburetor body for the attachment of the air cleaner fabric.

In the embodiment shown in Figs. 1 to 8 85 inclusive, the operation is as follows: Fuel enters a conventional float chamber 15, see Fig. 1, and passes through duct 17 to an annular fuel supply duct 18. Fuel then passes through openings 121 in the annular submerged orifice plate 21 and into the progressively elongated fuel nozzles 25, see Figs. 1, 3 and 4. Air enters the laterally directed and radially arranged air ducts 26 in the parted or two piece cylindrical housing 10. These 90 ducts are arranged in a spiral series, see Figs. 1, 3 and 5, and progressively decrease in area, see Figs. 1, 3, 5 and 6. Two such series of ducts are provided, see Fig. 5. The air passes through the ports 33 in the cylindrical body 95 100

30 which constitutes the throttle. These ports are elongated and somewhat triangular in outline and a pair is provided. A port 33 is adapted to successively register with two or more of the air ducts 26. When ports 33 register with the air ducts 26, air is drawn into the interior of the carburetor body by means of the suction of the engine cylinders.

As the air passes over the upper open ends 10 of fuel nozzles 25, it induces a flow of fuel therefrom, in a predetermined ratio to the entering air, controlled by the size of the orifices 121 in the plate 21, and air bleed holes 27, see Figs. 4 and 5, in inserts 27', see Fig. 1, 15 and downwardly directed passages 28, see Figs. 3 and 4. Passages 28 are formed in the wall 10 and terminate in recesses 27'' which receive members 27'. The air from passages 28 mixes with the fuel in the nozzles 25 20 since these are interconnected by means of slots 123, in rotatable plate 23, see Figs. 1, 3 and 7. Plate 23 is mounted in superposed relation to plate 21. Plates 23 and 21 are interposed between the two parts of the cylindrical body 10. They have the superposed seats 20, 22 and 24. Plates 23 and 21 are centered by the collar 120 formed upon one 25 part of the cylindrical housing 10 and said collar also centers the upper part of said housing 10. The cylindrical throttle 30 is retained within the upper part of the housing 10 and seats upon the collar 120 at its lower end. The throttle is operated by any suitable linkage arranged to be under the 30 control of the operator. In Figure 1 the rotating throttle barrel 30 and the throttle actuating lever arm 31 are firmly attached to the rotatable rod 32. Swinging arm 31 through any convenient angle results in a like motion of throttle 30. Air is admitted from two sources. Through the ducts 26, the total amount of air admitted is controlled by the number and amount of the ducts 26 in registration with the ports 33. Air is also admitted through the air bleed openings 27, the amount thereof being adjustable, see Fig. 4, and this air passes through passages 28 to the cross channels 123 in the plate 23 and thence mixes with the fuel and passes outwardly through the fuel ducts 25.

Fuel is supplied to the fuel ducts 25 from the annular channel 18 communicating therewith when the ports 121 in plate 21 register with the cross channels 123 in plate 23 and said cross channels register with the nozzles 25. The relative amount of fuel supplied to each nozzle can be adjusted by controlling the degree of registration of ports 121 and 123. Likewise the amount of air supplied through the air bleed openings 27 can be adjusted at the intake port point and the amount may further be controlled by determining the amount of registration between the cross passages 123 and the air bleed passages 28.

The total amount of air and fuel can be

readily controlled in normal use by rotating the throttle cylinder 30 the proper amount. The usual type of mechanism for adjusting the annular plates 21 and 23 is omitted and any conventional type permitting annular plate movement will be satisfactory.

During partially closed throttle operation the fuel will find a level in certain of the fuel and air bleed nozzles shown in Fig. 3 as 25 and 28 respectively, thereby furnishing a reservoir of extra fuel, to temporarily supply an enrichment of the mixture upon sudden opening of the throttle, as required by a sudden demand for power or acceleration, as in an automotive vehicle. In idling or with very small throttle openings, all the air used by the engine is drawn in through relatively small openings, with resulting high velocities and excellent atomization of fuel.

By admitting air and fuel through both sides of the carburetor body simultaneously the pressure differences are equalized, so that the carburetor throttle is balanced and free to move with a minimum of frictional resistance and wear. This is a valuable improvement as compared with the conventional type of butterfly throttle.

The construction of the throttle permits the fuel to enter the engine without the usual impinging upon the surface of the throttle, as is the case with the conventional butterfly design. This results in a higher degree of atomization and an avoidance of undue coalescence of the fuel.

In Figs. 14 to 17 inclusive, a sleeve type throttle construction is illustrated wherein like or similar parts have reference numerals increased by 50. Thus the throttle is indicated by the numeral 80, the air duct by 76, the fuel nozzle by 75, the air bleeding port by 77, the plate by 70, the carburetor bowl by 65, the actuating shaft, which is of the sleeve type, by 82, and the base including the same by 69, the mixing chamber by 84 and the actuating lever by 81.

In Fig. 14 there is shown suitable mechanism consisting of the bell crank arm 81 with the yoked end 181 arranged to slidably move the collar 85 and shaft 82. Said bell crank is suitably fulcrumed as upon the body of the carburetor and the opposite end may be connected to suitable linkage for manual control. The operation of this type of throttle is through the axial sliding action instead of rotating action. In the first modification described the throttle was oscillated or adequately reciprocated while in the second modification the throttle is rectilinearly reciprocated for obtaining fuel control.

As shown in these several figures and particularly Figs. 14 and 15 the individual air ports 26 through the body of the carburetor of the first modification are replaced by single port 76 upon opposite sides of the substantially rectangular shaped body. These

air ports are arranged in a slanting position, and, therefore, inclined relationship, so that the throttle is of substantially uniform shape and simpler in construction. In 5 this construction the fuel mixture does not pass through the ports but since these ports are the edges of notches, the mixture passes over the edge thereof and into the mixing chamber 84 of the carburetor.

10 A further improvement in operation at low speed with wide open throttle is secured by means of movable plates 88, hinged and affixed to the manually operated portion of throttle 80. These are maintained in a vertical position, by spring 89, when the throttle is wide open and air is entering the carburetor at very low flow rates. It will be noted in Figure 16, 15 that these movable plates 88 do not entirely cover the air ports 76 when in a vertical position as shown in Figure 15. This results in a high air velocity through the reduced air port opening, and consequent aspiration of fuel through the fuel nozzles 75, in a sufficient quantity to maintain a rich enough fuel air 20 mixture ratio to secure proper combustion in the engine cylinder. This would not otherwise be possible if the air ports were fully uncovered and the engine speed were very low.

25 As the engine speed increases with the throttle still fully opened, the movable plates 88 are pressed inward by the entering air, thereby automatically admitting further air and fuel in the proper variable combustible ratio and in amount equal to the engine demand.

Another embodiment of the invention relates to that type of throttle which might be either rotated like the first modification or axially moved like the second modification. 30 In either instance the throttle uncovers the air ducts and admits air and fuel to the engine. Such a modification is illustrated in Figs. 11 to 13 inclusive. In these figures substantially like or similar parts are indicated by 35 similar numerals increased by 20, thus numeral 46 indicates the air ports, 45 the fuel nozzles, 52 the actuating shaft 51 the actuating member therefor, herein shown in the form of a lever arm. The fuel supply channel is indicated by 38, the supply line thereto by 37, the carburetor bowl by 35, the air bleed ports by 47, the air bleed passages by 48, the air bleed and fuel mixing plates by 42, and the fuel controlling plate by 40.

40 In this form of the invention, the several parts instead of being concentrically arranged and circularly arranged are arranged in superposed relation and in multiple and parallel arrangement, see particularly Fig. 12. 45 While the cylindrical throttle 50 is herein shown specifically adapted for rotation, the shaft 52 might be elongated, and in this event it might be axially reciprocated as in the modification last described and by substantially 50 the same operating mechanism. Fig. 13 il-

lustrates sufficient clearance at the left hand portion of said figure to permit the sleeve type throttle to reciprocate and accomplish substantially the same purpose or fuel control as if it were rotated.

70 It has been demonstrated experimentally, and is of common knowledge to those skilled in the art of carburetion that, when fuel is fed to an engine manifold in a highly atomized state two very important and valuable 75 results are obtained. These are: first, better distribution of the fuel to the engine cylinders with less dependence upon special manifold shapes, and second, much leaner mixtures 80 of fuel and air may be used with satisfactory engine performance, thereby resulting in better economy in the use of fuel.

85 Accurate proportioning is also essential in the securing of economy because closer approach may be made to the ideal fuel-air mixture ratios, without at any time having a failure in power due to the introduction of non-combustible mixtures into the engine, known as "lean spots" in the proportioning characteristics.

90 The constructions disclosed above provide simple and inexpensive mechanisms for attaining these superior conditions in a new and novel manner, as compared with conventional mechanisms.

95 I claim:

A carburetor including a hollow cylindrical throttle having a substantially polygonal opening therein, a casing including a plurality of air passageways therethrough arranged in linear relation and with increasing area and adapted for progressive registration with the throttle opening, a fuel supplying jet in each of said passageways, an air vent passage and a fuel storage reservoir communicating with each jet, said casing including a fuel supply channel common to all jets, a plate having ports therein communicating with the channel and jets and forming a cover for said channel, and another plate having elongated slots 100 therein, each slot communicating with a port of said first mentioned plate and a jet and an air vent passage, said slots connecting each jet and an air vent passage and the fuel supply channel and forming a fuel reservoir. 105
